OPEN COIL ELECTRIC HEATER

Amos W. Hackman, Kirkland, Ill., assignor to Tuttle Electric Products, Inc., Kirkland, Ill., a corporation of Illinois

Application March 26, 1957, Serial No. 648,659

4 Claims. (Cl. 219—19)

This invention relates to open coil heating units of the type in which a long helical coil of resistance wire is supported in an open or exposed manner by a grille or lattice type metal frame having spaced apart electrical insulators through which the resistance coil extends, the invention having reference more particularly to the electrical insulating of such units.

Such heating units are commonly used in appliances, such for example as clothes dryers and the like, to heat air by circulation thereof through the open coil heater, and as the appliances in which these heating units are used are generally made of conductive materials, it is important that there be no current leakage from the heating unit which might cause shock to the operator of the appliance.

Inasmuch as the frames of such heating units are of metal, it is necessary to insulate the resistance coil electrically therefrom and, as such heaters are operated at high temperatures, insulators of ceramic material are employed for the purpose and are depended upon to safeguard the appliance with which the heater is used, against communication of any current thereto from the heating resistance.

Such insulators, however, have the characteristic that when they are highly heated, as they oftentimes are in heating units of the type to which the invention pertains, they acquire a slight surface conductivity which is likely to permit sufficient current leakage to cause shock to the operator or attendant of the appliance unless the surface distance from the place or places of contact of the resistance coil with the insulator to the nearest metal part to which the insulator is secured is sufficient to become a bar to any such leakage, and great difficulty has been experienced heretofore in providing a satisfactory ceramic insulator with sufficient surface distance to preclude such leakage.

Flat disk type insulators which were commonly employed with a central opening therethrough to accommodate the resistance coil and with a peripheral formation such, for example, as a V-edge for interlocking with encircling or partially encircling metal parts of the frame for securing the insulator thereto, could not be provided with sufficient surface distance to preclude current leakage without making the insulator objectionably large, and tubular insulators were employed which were provided midway between their ends with an annular V-edged rib therearound for interlocking with the encircling or partially encircling parts of the metal frame and these tubular insulators could be made of such length to satisfactorily avoid current leakage, but it was found that when these tubular insulators were made of sufficient length to preclude current leakage, they caused over-heating of the portion of the resistance coil therein and premature burn out of the resistance coil on this account.

The principal objects of this invention are, to provide improved open coil metal frame heaters of the type above referred to; to avoid the above mentioned difficulties ex-

perienced with previous open coil metal frame electric heaters; to provide heating coil insulation which effectively eliminates current leakage; to minimize the size of insulators required to avoid current leakage; to provide supplemental facilities for added certainty of complete safeguard against shocks to the operator or attendant of the appliance with which the heating unit is used; and to accomplish these improvements with facilities which are readily adaptable to open coil heaters of the present type without material alteration thereof, these and other objects being accomplished as pointed out more particularly hereinafter and as shown in the accompanying drawings, in which:

Fig. 1 is a top view of a heater embodying the improvements of this invention;

Fig. 2 is an enlarged end view of one of the resistance coil supporting insulators of Fig. 1, taken on the line 2—2 of Fig. 1, and showing a portion of the insulator support;

Fig. 3 is a sectional view of the insulator and insulator support of Fig. 2 taken on the line 3—3 thereof;

Fig. 4 is an end view of one of the mounting bracket assemblies of the heater of Fig. 1 taken on the line 4—4 thereof;

Fig. 5 is an end view of the insulator of the mounting bracket assembly of Fig. 4;

Fig. 6 is a sectional view similar to Fig. 3 of a modification of the insulator of Figs. 2 and 3;

Fig. 7 is a top view of another form of heater made in accordance with the present invention;

Fig. 8 is an enlarged view of one of the mounting bracket assemblies of Fig. 7, partly in section on the line 8—8 of Fig. 7;

Fig. 9 is a sectional view of the assembly of Fig. 8 taken on the line 9—9 thereof;

Fig. 10 is a perspective view of one of the mounting brackets of Fig. 7;

Fig. 11 is an end view of the insulator of the mounting assembly of Fig. 8;

Fig. 12 is a side view of the insulator of Fig. 11;

Fig. 13 is a top view, with an intermediate portion broken away, of another form of heater made in accordance with the present invention;

Fig. 14 is an enlarged view of the electrically insulated connection of the heater mounting facilities of the Fig. 13 heater taken on the line 14—14 thereof.

Fig. 15 is a view in section from front to rear, of a clothes dryer showing the application of a heater of the present invention thereto; and

Fig. 16 is a view of the clothes dryer of Fig. 15 taken on the line 16—16 thereof.

Referring to the drawings, and particularly to Figs. 1 through 5 thereof, the heater shown therein comprises a long helical coil 20 of resistance wire which extends back and forth through ceramic insulators 21 carried by an open metal frame, which is indicated as a whole by the reference numeral 22 and has a heavy border wire bent in a U-shape with two laterally spaced legs 23 connected by a transverse portion 24 thereof at one end of the frame 22.

The transverse portion 24 has a plate 25 secured thereto midway of its length to support two terminal stems 26 and 27 to which the opposite ends of the helical resistance coil 20 are connected, as indicated respectively at 28 and 29, and the terminal stems 26 and 27 are carried by separate electrical insulators 30 which are secured in spaced apart relation to the plate 25 so that the terminal stems are electrically insulated from one another and from the plate 25.

A series of spaced apart parallel insulator supporting members 31 and 32 extend crosswise of the frame 22

between the legs 23 thereof and are secured together to laterally spaced parallel lengths 33 of light bar stock that extend lengthwise of the frame 22, the transverse insulator supporting members 31 and 32 being welded to the bars 33 as indicated at 34.

The two end ones 31 of said insulator supporting members are longer than the intermediate ones 32, and are connected at their opposite ends to the legs 23, in a manner hereinafter explained, so that the entire assembly of insulator supporting members 31 and 32, and bars 33 and insulators 21 is supported solely by the legs 23 of the border wire and solely by the connection of the ends of the two end insulator supporting members 31 therewith.

The insulators 21 which are of ceramic material are of short generally tubular form as shown in Figs. 2 and 3, formed with an external V-shaped rib 35 extending therearound midway between the ends thereof for mounting purposes, and each of the insulator supporting members 31 and 32 is composed of a pair of narrow metal strips, those of the members 31 being indicated at 32^a and 31^b and those of the members 32 being indicated at 32^a and 32^b, with one strip of each pair overlying the other strip of that pair and both provided with matching opposed substantially semicircular portions 36 which are adapted to conjointly encircle the surrounding rib 35 of an insulator to hold the latter therebetween. The portions 36 are V-shaped in cross section to interlock with the ribs 35 of the insulators and the portions of the metal strips 31^a and 31^b and 32^a and 33^b between the semicircular portions 36 are flat and secured together as for example by spot welds 37.

The corresponding insulators 21 of all of the supporting members 31 and 32 are in line and each insulator 21 has a central opening 38 therethrough through which the resistance coil 20 is threaded to provide spaced apart parallel lengths thereof with return bends 39 beyond the insulator supporting members 31 as shown in Fig. 1.

Heretofore insulators of the tubular type had a cylindrical opening extending therethrough of only a slightly larger diameter than the outside diameter of the coil 20 and by reason of this cylindrical form of the opening the resistance coil could contact the interior of the insulator throughout substantially the entire length of the opening and on this account a long tubular insulator was required for adequate length of insulator surface from the place of contact of the resistance coil with the interior of the opening to the metal part of the frame which encircled or partially encircled the insulator for supporting the latter in the frame.

Moreover, because of the cylindrical form of the insulator opening and the cylindrical form of the resistance coil the latter was in such close proximity to the encircling insulator throughout the length of the opening thereof that the insulator became highly heated and the portion of the resistance coil therein readily became overheated and would burn out prematurely within the insulators.

It is an important feature of the present invention that the opening through the insulator is reduced in size midway between the ends thereof so that the resistance coil is held centrally in the opening solely by facilities occupying only a short portion of the length of the opening midway between the ends thereof, the insulator opening at both sides of this midway place being of sufficiently large size so that there not only is no possible contact of the resistance coil with the insulator except at the place midway of the length of the insulator opening but the resistance coil at both sides of this midway place is sufficiently remote from the surrounding wall of the opening that the wall may be said to be spaced from the coil in petticoat relation so as to greatly minimize the heating of the insulator and overheating and burn out of the resistance coil.

Thus the length of insulator surface from the place of

possible contact of the resistance coil with the insulator to the metal parts which encircle the insulator for supporting the latter on the frame is increased by the length of internal surface of the insulator at each side of the midway place where the resistance coil is supported thereon and a shorter length of insulator may be employed than heretofore with assurance of safeguard against current leakage, and this, as well as the remoteness of the resistance coil from the wall of the insulator opening at each side of the midway place also provides assurance against overheating and burn out of the resistance coil.

For localizing the support of the resistance coil and contact thereof with the insulator at a place midway of the length of the insulator opening, the insulator may be provided with a plurality of circumferentially spaced internal projections 40 as shown in Figs. 2 and 3, three such projections being there shown and these may be narrow axially extending ribs as shown in Fig. 2 and need be only of such axial length to bridge the space between convolutions of the resistance coil as shown in Fig. 3, and except at the projections 40 the size of the opening 38 is such that the resistance coil 20 is safely spaced from the wall thereof to avoid any possible contact therewith and provide a substantial air gap therebetween to minimize heating of the insulator.

Instead of employing a series of projections or ribs 40 as shown in Figs. 2 and 3 the insulator may be formed as shown in Fig. 6 with an opening of a reduced diameter as indicated at 41 to support and contact the resistance coil only at a place midway of the length of the insulator opening and at opposite sides of the midway place 41, the insulator opening may be flared outwardly as indicated at 42 to an enlarged size at each end considerably in excess of the diameter of the resistance coil, thus producing the desired petticoat effect.

For additional assurance of non-conductivity of current from the heating unit to the appliance on which it is mounted, I have also provided the unit with mounting facilities by which the resistance coil supporting portion of the frame of the unit is electrically insulated with certainty from the appliance, and for this purpose the two end insulator supporting members 31 are secured at their opposite ends to the exterior of tubular insulators 43 which have central openings 44 through which the arms 23 of the border wire of the frame extend, and the other insulator supporting members 32 are of shorter length so that they have no connection with the arms 23 and the only connection of the assembly of frame parts 31, 32 and 33 with the border wire of the frame is through the end insulators of the end members 31.

Obviously the members 32 may be like the members 31 and provided with insulators 43 at the opposite ends mounted on the border wire arms 23, but the construction illustrated and described above is preferred.

The insulators 43 are of ceramic material and are preferably secured to the end members 31 in the same manner as the insulators 21 are secured to the members 31 and 32, and for this purpose the insulators 43 are provided with an external V-shaped rib 45 extending therearound midway between the ends of the insulator and the upper and lower strips 31^a and 31^b of the members 31 are provided with matching opposed semicircular formations 46 which are like the semicircular formations 36 and of V-shape cross section to interlock with the ribs 45 of the insulators 43, and the two strips 31^a and 31^b are flat and arranged in face to face engagement and secured to one another, as for example by spot welding, at opposite sides of the insulators 43 so that the latter are permanently secured in place.

Each insulator 43 is straddled by spaced arms 47 of a mounting bracket or plate 48 by which the heating unit is mounted on the appliance with which it is used, the ends of the arms 47 being looped around the border wire 23 as shown at 49, the opening between the arms 47 being of such depth that ample clearance is provided

beyond the outer end of the frame member 31 to preclude any possible contact of said frame member end with the bracket 48.

These heating units may be flat or arched transversely or of any other form required for the particular appliance on which used, an illustrative application of such units being shown in Figs. 15 and 16 in a clothes dryer of conventional form in which a cylindrical drum 50 having a peripheral wall 51 which is apertured, as indicated at 52, is mounted to rotate within a closed cylindrical shell 53.

This drum 50 and its enclosing cylindrical shell 53 are mounted within an outer casing 54 and an access opening 55 is provided, closed by a door 56 for depositing in and removing from the interior of the drum 50 clothes which are tumbled therein by the rotation of the drum for drying.

The outer casing 54 has one or more air inlet openings through which air is supplied to the interior thereof and the cylindrical shell 53 has an opening 57 therethrough at the top through which air is suppliable from the interior of the outer casing 54 to the space between the cylindrical shell 53 and from that space through the perforations 52 to the interior of the drum 50.

An exhaust fan 58 is connected to the cylindrical shell 53 at the bottom to exhaust air from the interior of the shell and the space between the shell 53 and the drum 50 is sufficiently separated, as for example by partition means 59 extending inwardly from the wall of the shell 53, into upper and lower sections so as to cause the air entering through the opening 57 into the upper section to pass into and through the drum 50 to the lower section in the exhaust operation of the exhaust fan 58.

A heater such as described above is mounted directly above the opening 57 as indicated at 60 to heat the air supplied to the interior of the shell 53 and is preferably transversely arched as indicated in Fig. 16 to correspond to the cylindrical wall of the shell.

The mounting brackets or plates 48 may be of any shape or form required for mounting the heating in the appliance with which it is used and for the mounting thereof in the dryer of Figs. 15 and 16 the brackets 48 extend downwardly as indicated at 61 and have an outwardly turned portion 62 at the lower end with slots 63 or openings for bolts or screws by which the heater is secured to the shell 53 at opposite sides of the opening 57 and held in a slightly elevated position above the opening 57.

This heater, being at the top of the shell 53 is close to the top wall 64 of the outer cabinet or casing 54 and the latter is preferably provided on the underside of the top wall 64 and spaced therebelow with a reflector plate 65 which overlies the heater 60 to reflect heat downwardly therefrom toward the opening 57.

The dryer casing 54, shell 53 and various other parts within the casing 54 are of metal and assembled in a conventional manner which generally permits electrical conductivity from one part to another, and moreover these parts are usually exposed to moisture conditions which promote electrical conductivity by reason of which it is essential that the resistance coil 20 be safely insulated electrically therefrom, and the electrical insulation of the mounting brackets 48 from the frame of the heating unit provides an additional and effective safeguard for this purpose.

The heaters of Figs. 7 and 13 are of the same construction as the heater of Fig. 1, except as hereafter explained and the corresponding parts hereof are indicated by the same reference numerals as applied thereto in Fig. 1.

In the construction of Fig. 7, the marginal frame of Fig. 1 is omitted and the terminal stems 26 and 27 and their insulators 30 are mounted in a plate 66 which is adapted to be mounted directly on and supported by

the clothes dryer or other appliance with which the heater is employed.

Moreover in the Fig. 7 construction, mounting brackets 5 are secured directly to the insulators at the outer ends of the end insulator supporting members 31, these brackets being indicated at 67 and the insulators to which they are secured being indicated at 68.

These insulators 68 differ from the corresponding insulators of Fig. 1 in the respect that each of the insulators 10 68 has a slot like opening 69 extending therethrough to accommodate a flat tongue 70 of the mounting bracket 67 by which the bracket is secured thereto.

This mounting bracket 67 is of the same general form as the brackets 48 of Fig. 1 and has a pair of laterally spaced arms 71 and 72 with the tongue 70 integral with the arm 71 and projecting therefrom toward the other arm 72 and the latter arm has its outer end folded around the extremity of the tongue 70 as indicated at 73.

Thus before the fold 73 is formed, the tongue 70 may be bent away from the arm and the insulator 68 then slipped onto the tongue 70 after which the tongue 70 is then bent back to the position in which the outer end of the arm 72 is folded around the extremity of the tongue 70 to lock the bracket 67 on the insulator 68.

The insulator 68, like the insulators 43 of Fig. 1, has an annular rib 74 therearound by which the insulator 68 is secured in opposed semi-circular seats 36 of the upper and lower strips 31^a and 31^b of the insulator supporting members 31, but the annular rib 74 of the insulators 30 30 68 of the Fig. 7 construction are preferably provided with diametrically opposed protuberances 75, as shown in Figs. 11 and 12, to engage between outwardly bent portions at the extremities of the semi-circular portions 46 between which the insulators 68 are interposed.

Thus the insulators 68 are keyed against turning in the seats of the semi-circular portions 46 and as the bracket 67 is oriented in a fixed position with respect to the insulator 68 by reason of the engagement of the flat tongue 70 thereof with the slot like opening 69 of the insulator 68, the brackets 67 may be held in a fixed supporting relation to the heater of Fig. 7.

In the heater of Fig. 13 wire members 76 and 77 are provided at the opposite ends of the heater for mounting the heater on an appliance, each said members 76 and 45 77 having loops 78 at their opposite ends to accommodate fasteners for that purpose, and the wire member 76 has a plate 79 secured thereto by which the terminal stems 26 and 27 and their insulators 30 are supported.

The end insulator supporting members 31 of the Fig. 50 13 heater have insulators 80 secured to their ends in a different manner than the insulators 43 are secured to the members 31 in the Fig. 1 construction, the insulators 80 being similar to the insulators 68 of the Fig. 7 construction in the respect that the insulators 80 have a slot like opening 81 therethrough to receive therein the outer ends of the two strips 31^a and 31^b of the members 31 as shown in Fig. 14.

Each insulator 80 has an annular rib 82 therearound and the wire member 76 has a pair of brackets 83 secured thereto and connected to the insulators 80 at the opposite ends of one of the insulator supporting members 31 and the other wire member 77 has a pair of similar brackets 83 thereon and connected to the insulators 80 at the opposite ends of the other insulator supporting member 31.

These brackets 83 are composed of two strips 83^a and 83^b, one overlying the other and provided with opposed semi-circular portions 84 engaged around and secured to the respective wire members 76 or 77 and at their other ends these strips 83^a and 83^b have opposed semi-circular portions 85 engaging the annular rib 82 of an insulator 80 to secure the latter therebetween.

The strips 83^a and 83^b are permanently secured to one another, as for example, by welding and the insulators

80 preferably have diametrical protuberances 86, like those at 75 in Figs. 11 and 12, to key the insulators 80 against turning movement in the seats 85.

The openings 81, 69 and 44 of the respective insulators 80, 68 and 43 may be like those of the coil receiving insulators 21 in the respect that they are of restricted size at a place midway between the ends thereof conforming to and closely confining the part engaged therein and are of enlarged cross section at opposite sides of that midway place, as indicated by dotted lines at 81^a in Fig. 14, and at 69^a in Figs. 9 and 11 and at 44^a in Fig. 5 to provide such clearance at opposite sides of such midway place that the part engaged in the opening contacts with the insulator only at the midway place of the opening.

With the constructions above described the resistance coil is not only safely insulated from the metal frame of the heater by insulators which avoid overheating and burn out of the resistance, but the heater is also provided with insulated mounting means as a part thereof which precludes with certainty any possible current leakage from the heater to the appliance with which it is used.

While I have shown and described my invention in a preferred form, I am aware that various changes and modifications may be made without departing from the principles of the invention, the scope of which is to be determined by the appended claims.

I claim:

1. An open coil heater of the class described comprising an electrically conductive frame with portions thereof spaced apart to provide openings through the frame from one side thereof to the other side thereof, a long helical coil of resistance wire which is carried by the frame and arranged circuitously thereon to extend across said openings of the frame and is energizable to supply heat, and electrically conductive mounting means by which the frame is securable to a support, the frame having thereon two sets of electrical insulators, one set of which is interposed between and electrically insulates the resistance coil from the frame and the other set of which is interposed between and electrically insulates the mounting means from the frame and wherein the insulators of both sets are substantially cylindrical bodies of insulating material each peripherally engaged in a metal holder and having an opening extending axially therethrough from end to end thereof through which a metal part extends for electrical insulation thereof from the metal holder, the axial openings of at least one set of said insulators having elongated enlarged opposite end portions thereof constituting the major portion of the length of the opening and extending oppositely from a narrow midlength expande of the opening which is locally restricted to hold the metal part therein in a substantially central position of annular spacing from the insulator throughout the length of said elongated enlarged opposite end portions of the opening.

2. An open coil electric heater of the class described comprising an electrically conductive frame, a long helical coil of resistance wire arranged circuitously on the frame, and a plurality of spaced apart electrical insulators by which the helical coil is mounted on and electrically insulated from the frame, said frame having spaced apart mounting portions in which the insulators are peripherally secured with opposite end portions of the insulators projecting from the mounting portions at opposite sides thereof, each of said insulators being provided with an opening through which the helical coil extends, said openings being formed with a narrow midlength portion and enlarged end portions extending oppositely from said narrow midlength portion, with each insulator contacting the coil at the portion thereof in the midlength portion of the opening to hold the coil centrally in the enlarged end portions of the opening, said enlarged end portions constituting the major por-

tion of the length of the opening and being defined by insulator portions which are annularly spaced from and skirt the helical coil at a distance therefrom in petticoat-insulating relation around the coil throughout the length of the enlarged end portions, with each of said last mentioned insulator portions being out of range of contact with the coil throughout the length of said enlarged end portions and with each of said enlarged end portions providing an annular air chamber around the coil for cooling thereof, said annular air chambers being open at their outer ends for free access of air thereto.

3. An open coil electric heater of the class described comprising an electrically conductive frame, a long helical coil of resistance wire arranged circuitously on the frame, and a plurality of spaced apart electrical insulators by which the helical coil is mounted on and electrically insulated from the frame, said frame having spaced apart mounting portions in which the insulators are peripherally secured with opposite end portions of the insulators projecting correspondingly from the mounting portions at opposite sides thereof, each of said insulators being provided with an opening through which the helical coil extends, said openings being formed with a narrow midlength portion and enlarged end portions which are of corresponding length and constitute the major portion of the length of the opening and extend oppositely from the midlength portion, with each insulator contacting the coil at the portion thereof in the midlength portion of the opening to hold the coil centrally in the enlarged end portions of the opening, each enlarged end portion being defined by an insulator portion which is annularly spaced from and skirts the helical coil at a distance therefrom in petticoat-insulating relation around the coil throughout the length of said end portion and provides an annular air chamber around the coil for cooling thereof, each said insulator portion which skirts the coil as aforesaid being out of range of contact with the coil throughout the length of said enlarged end portions, and said air chambers being open at their outer ends for free access of air thereto.

4. An open coil electric heater of the class described comprising an electrically conductive frame, a long helical coil of resistance wire arranged circuitously on the frame, and a plurality of spaced apart electrical insulators by which the helical coil is mounted on and electrically insulated from the frame, said frame having spaced apart mounting portions in which the insulators are peripherally secured with opposite end portions of the insulators projecting from the mounting portions at opposite sides thereof, each of said insulators being provided with an opening through which the helical coil extends, said openings being formed with a narrow midlength portion and enlarged end portions extending oppositely therefrom, with each insulator contacting the coil at the portion thereof in the midlength portion of the opening to hold the coil centrally in the enlarged end portions of the opening, said enlarged end portions conjointly constituting the major portion of the length of the opening and being defined by insulator portions which are annularly spaced from and skirt the helical coil at a distance therefrom in petticoat-insulating relation throughout the length of the enlarged end portions, with each of the insulator portions which skirt the coil as aforesaid being out of range of contact with the coil throughout the length of said enlarged end portions, and each of said enlarged end portions providing an annular air chamber around the coil for cooling thereof, said insulator having means about its midlength circumference projecting externally for interlocking engagement with said mounting portions of the frame, and said annular air chambers being open at their outer ends for free access of air thereto.
